SHOE STAND WITH POLISHING
CLOTH GUIDES

Gilliard J. Sherin, Seattle, Wash.

Application June 11, 1948, Serial No. 32,458

1 Claim. (Cl. 15—266)

This invention relates to a shoe shining and cleaning means, and it has reference more particularly to such means designed to be manually operated by the person wearing the shoes that are to be cleaned or shined; it being the principal object of the invention to provide a practical, inexpensive, effective and easy to use means for the quick dusting off, shining or polishing of shoes.

More specifically stated, it is an object of the invention to provide a shoe shining means that is especially useful in homes, offices or shops merely for the wiping off of dust or dirt, but which is also practical for shining after polish has been applied, and which device comprises a foot plate on which the foot that wears the shoe that is to be shined or cleaned is rested, during the shining operation, and which plate is equipped along opposite sides thereof with guides about which a strip of suitable polishing or shining cloth may be passed, to guide the strip across the foot and hold it in shining contact with the shoe as it is reciprocated endwise; this being accomplished by the user by grasping the strip at its opposite ends.

Still further objects of the invention reside in the details of construction, combination and relationship of parts, and in the mode of use of the device, as will hereinafter be fully described.

In accomplishing these and other objects of the invention, I have provided the improved details of construction, the preferred forms of which are illustrated in the accompanying drawings, wherein:

Fig. 1 is a top, or plan view of the foot plate which comprises a principal part of the present invention, particularly illustrating the location and application of the guide rods for the polishing strip.

Fig. 2 is a side view of the same.

Fig. 3 is a perspective view illustrating the use of the present device, and showing therein a position of the fabric strip for shining the toe portion of the shoe.

Referring more in detail to the drawings:

In its present preferred form of construction, the present device comprises a base plate, or what I will hereinafter refer to as the foot plate, 10. Preferably this plate comprises a single, flat piece of wood, cut substantially to the shape of the outline, in plan, of a shoe, and in dimensions longer and preferably somewhat wider than the shoes that are to be shined thereon. Across the toe end portion, the plate 10 is equipped on its under side with a support 11, comprising a strip

of wood about one inch high fixed rigidly thereto. When the plate 10 is placed properly on a floor or other surface for use, the cross strip 11 will operate to give the plate an upward slope from its heel to toe portion that is desirable and advantageous to easier use of the device.

Fixed to the plate 10, lengthwise thereof, and along its opposite sides thereof, and spaced about one-half inch from the plate edge, as best noted

10 in Fig. 1, are rigid guide rods 12—12. These rods are formed from a continuous strip of stiff wire. The strip is bent intermediate its ends to provide a saddle portion 13 in which the heel end of the plate is disposed. The vertical portions 14—14 at opposite sides of the saddle are held by staples 15 driven into opposite sides of the plate. The rods 12—12 extend forwardly along the plate as seen in Fig. 1 and at their forward ends are turned inwardly, then vertically downward, as at 16, then again inwardly so that the end portions 17—17 are secured between the bottom of the plate 10 and the supporting block 11. The parts 16 are secured by staples 18 applied thereover and driven into the side edges of the plate.

The rods so assembled are held in fixed relationship with the plate and the rods are of such rigidity as to withstand the pull of the shining cloth in use as presently described.

30 In connection with the foot plate as above described, I also use a flexible strip of polishing cloth 20, or other suitable material, about three inches wide and from four and one-half to five feet long. In use, this strip is threaded across the top of the plate 10 and passed downwardly 35 at the opposite edges of the plate beneath the rods 12—12, and its opposite ends are then drawn upwardly by the user by grasping them in the hands as shown in Fig. 3.

40 To use the device for shoe shining or polishing, the plate 10 is placed on the floor, or upon any other supporting surface as shown in Fig. 3, and the foot wearing the shoe that is to be shined is then planted firmly upon the plate, as nearly centered as possible, and down pressure is applied to hold the plate firm. The portion of the applied shoe is placed beneath the strip where it crosses the plate 10 and between rods 12—12, and the parts then assume the position as shown 50 in Fig. 3.

By drawing the strip 20 taut, and reciprocating it endwise, it will effect the cleaning and shining of the engaged part of the shoe as is well understood by persons familiar with the art. The 55 entire outer surface of the shoe may easily be

covered, by working the strip forwardly or rearwardly along the guide rods 12-12 between toe and heel portions, and by tilting the foot or shifting it sidewise or endwise as may be required to permit that portion of the strip, as drawn between the guide rods, or as drawn from either guide rod to the hands, to be engaged with the shoe. A few uses of the device enables one to very effectively and thoroughly polish or clean the shoe. If a shoe polish is used, this can be applied to the shoe before the polishing cloth is used.

Devices of this kind may be made of various materials. If desired, the foot piece could be fixed to a supporting surface so that pressure or weight of the foot need not be applied to hold it in place.

Such shoe shining or cleaning devices are inexpensive, easy to use, and practical and effective for their intended uses.

Having thus described my invention, what I claim as new therein and desire to secure by Letters Patent, is:

A support for use in shoe shining operations comprising a foot plate adapted to be rested at the heel end upon the floor, a cross-bar fixed to the said plate at the underside and across the toe portion to support that portion at a substantial elevation above the heel end, and a single length of stiff wire bent at a medial portion to

form a transverse saddle in which the heel end portion of the plate is seated and secured; the opposite remaining portions of the wire being extended along the opposite side edges of the plate in spaced relation thereto for the guiding of a polishing strap, and having their end portions turned inwardly to the sides of the plate, then downwardly, then, inwardly and applied between the bottom of the plate and said cross-bar, and staples applied to the plate about the downwardly turned portions of the wire to secure them against outward displacement.
